UNITED STATES PATENT OFFICE.

JEREMIAH M. WATSON, OF SHARON, MASSACHUSETTS.

HEEL-STIFFENER FOR BOOTS AND SHOES.

SPECIFICATION forming part of Letters Patent No. 247,787, dated October 4, 1881.

Application filed May 3, 1881. (No model.)

To all whom it may concern:

Be it known that I, JEREMIAH M. WATSON, of Sharon, of the county of Norfolk and State of Massachusetts, have invented a new and useful Improvement in Heel-Stiffenings for Boots or Shoes; and I do hereby declare the same to be described in the following specification and represented in the accompanying drawings, of which—

10 Figure 1 is an external elevation, Fig. 2 an internal view, Fig. 3 a longitudinal section, and Fig. 4 a transverse section, of a boot or shoe heel counter provided with my invention, the nature of which is defined in the claim hereinafter presented.

In carrying out my said improvement I combine with a boot or shoe counter made of leather or leather-board a metallic flexible or elastic re-enforce or stiffening-plate, capable of 20 forming, without wrinkling, with the counter, to the shape of the last while the shoe or boot containing such counter is lasted or being lasted, the object of the re-enforce being to prevent the counter, while the boot or shoe 25 may be in wear, from yielding so as to cause what is termed "running down at the heel," which is particularly apt to follow with counters of leather or leather-board when wet or water-soaked.

30 The re-enforce or yielding metallic plate B, which I combine with a boot or shoe counter, A, is notched or provided with a range of teeth, *aa* or *a'a'*, both at top and bottom. As shown in Fig. 2, the apex of each angular space 35 between any two next adjacent of the teeth of such range is opposite the middle of the base of a tooth of the fellow range of teeth, each tooth being triangular in shape. This arrangement renders the plate stronger and less liable 40 to break than would be the case were the apices

of the spaces between the teeth of one range directly opposite those of the teeth of the other range. The re-enforce so made of thin metallic plate is laid flatwise on the inner side of the counter and lengthwise thereof, and is connected to such counter by bending at a right angle or thereabout, near its apex, each tooth of the upper range, and inserting through the counter the part so bent, and upsetting or clinching it down upon the counter, such being with 45 respect to each tooth, as shown in Fig. 4. Without the two series of teeth arranged very nearly together, as shown, the re-enforce will not readily bend laterally and longitudinally with the counter and take the proper or required 50 form without wrinkling during the process of lasting a shoe or boot having such a counter; but with the two ranges of notches or teeth the necessary flexures or bendings of the re-enforce, both longitudinally and laterally of it, follow without danger of it becoming 55 ridged, wrinkled, or broken.

I am aware that it is not new to make a counter entirely of metal, nor is it new to fix upon a counter, at its lower part, a metallic 60 plate. Consequently I make no claim to such in the abstract; but

What I claim as my invention is as follows:

As an improved article of manufacture, a heel-stiffening, substantially as described, consisting of the counter of leather or leather-board, and of the flexible or elastic metallic plate or re-enforce, notched or having teeth at its opposite edges, and arranged and combined with the said counter essentially as set forth. 70 75

JEREMIAH M. WATSON.
